UNITED STATES PATENT OFFICE.

CLARK T. HENDERSON, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC WINDING.

1,239,008.

Specification of Letters Patent.

Patented Sept. 4, 1917.

Application filed July 6, 1914. Serial No. 849,301.

To all whom it may concern:

Be it known that I, CLARK T. HENDERSON, a citizen of the United States, residing at Milwaukee, in the county of Milwaukee and State of Wisconsin, have invented new and useful Improvements in Electromagnetic Windings, of which the following is a full, clear, concise, and exact description, reference being had to the accompanying drawing, forming a part of this specification.

This invention relates to improvements in electromagnetic windings.

In the winding of electromagnets it has been found highly advantageous to interpose between the axial layers thereof thin sheets of material, preferably insulation, for purposes well understood in the art. Also, in practice, it is highly desirable and often a requirement that the completed winding be impregnated to thoroughly insulate the same and eliminate air pockets therein. However, where the magnet is wound as aforesaid, it has been proven very difficult, if not impossible, to effect thorough impregnation, due to the fact that the insulation completely prevents ingress of the impregnating material radially of the winding, and furthermore, often laps over the ends of the winding to prevent axial ingress of the impregnating material.

This invention has among its objects to provide a winding of the aforesaid character which may be readily and thoroughly impregnated.

Various other objects and advantages of the invention will hereinafter appear.

For the purpose of more fully and clearly disclosing the nature and characteristic features of the invention, one embodiment thereof has been illustrated in the accompanying drawing, in which,

Figure 1 is a perspective view of a magnet winding, partially in section; and,

Fig. 2 is an enlarged perspective view of a portion of one of the sheets of insulation employed in said winding.

Referring to Fig. 1, the same shows a magnet winding formed of an insulated conductor 1 wound helically in a plurality of layers with sheets 2 of insulation interposed between the layers. The insulation, how-

ever, is, as best illustrated in Fig. 2, provided with perforations 3 of any preferred size and arrangement.

As will be understood the winding is formed by coiling the conductor 1 about a suitable core and inserting the sheets 2 of insulation during the winding process. Also, for purposes well understood, the insulation employed is preferably of sufficient width to provide projecting marginal portions 4 at opposite ends of the winding and it is such marginal portions that have added to the difficulties of impregnation as above set forth. The pressure of the impregnating material against the winding has caused said marginal portions of the insulation to fold over, as indicated by dotted lines, thus tending to seal the winding against further impregnation.

However, when the winding is constructed as above described, the same enables ingress of the impregnating material radially of the winding through the perforations 3 in the sheets of insulation. Of course, the conductor in passing over the perforations tends to obstruct the same but said perforations may be readily so proportioned and arranged as to insure passages through each sheet of insulation at an adequate number of points. In practice it is desired to provide a minimum number of perforations and to provide perforations of minimum dimensions to preserve the usefulness of the insulation sheets.

A common method of impregnation consists in placing the winding to be impregnated in an air tight receptacle, then evacuating said receptacle, and then forcing impregnating material into said receptacle under a relatively high pressure. Thus, where the winding is penetrable both axially and radially as above described, it will be apparent that the same may be readily and thoroughly impregnated even though ingress of the impregnating material be resisted at the ends of the winding, as aforesaid.

What I claim as new and desire to secure in Letters Patent is:

An electromagnetic winding comprising a conductor wound helically in layers and

perforate sheets of insulation interposed between adjacent layers thereof, the perforations of said sheets of insulation being arranged to provide passages radially through said winding to facilitate impregnation thereof.

In witness whereof, I have hereunto sub-

scribed my name in the presence of two witnesses.

CLARK T. HENDERSON.
